PORTABLE ADJUSTABLE PUMP

Frank M. North, Corcoran, Calif.

Application November 17, 1938, Serial No. 241,053

4 Claims. (Cl. 103—218)

This invention relates to an improved portable pump adapted to be mounted on motor vehicles such as tractors or trucks and provided with hoisting means for adjustably supporting the pumping unit.

It is a particular aim of this invention to provide a portable pumping apparatus adapted to be mounted on a truck or tractor, and adapted to be used for draining swamps or the like and for pumping rivers or streams for irrigating land.

More particularly, it is an object of this invention to provide a pumping apparatus including a pivotally mounted pump casing provided with pumping means actuated by the driving means of the vehicle to which the apparatus is attached and having supporting means for the free inlet end of the pumping unit by which said end may be readily raised when the apparatus is to be moved or lowered to any desired depth to submerge the inlet end of the pump casing in a body of water.

Other objects and advantages of the invention will hereinafter become more fully apparent from the following description of the drawings, which illustrate a preferred embodiment thereof, and wherein:

Figure 1 is a side elevational view of the apparatus,

Figure 2 is a top plan view of the same,

Figure 3 is an enlarged fragmentary horizontal sectional view taken along the line 3—3 of Figure 1, and

Figure 4 is an enlarged fragmentary vertical sectional view taken along the line 4—4 of Figure 2.

Referring more particularly to the drawings, wherein like reference characters designate like or corresponding parts throughout the different views, 10 designates a portion of one end of a motor vehicle such as a tractor, to which is secured the frame 11, which projects outwardly therefrom.

The frame 11 at its free end, is provided with the removable brackets 12 each provided with a plurality of alined openings 13 for a purpose which will hereinafter be described.

A pump tubing or casing 14, as shown, comprises a section 15 having an elbow 16 at one end disposed at an oblique angle to the remaining portion of the tubing 14, a section 17 joined to the opposite end of section 15 and a section 18 connected to the opposite end of section 17. Section 18 of the tubing 14 forms the inlet end of the pump casing and is tapered along its underside 19 from a point adjacent its secured end

outwardly to its free end and is open along its underside and along the line 19 to provide a mouth for the pump tubing 14.

A frame 20 is secured to section 15 adjacent its end 16 and including the pair of arms 21 which are secured by the fastenings 22 to the section 15 and which project therefrom in a plane parallel to the axis of the casing 14. The free ends of the arms 21 are pivotally connected by the fastenings 23 to the brackets 12 and it will be noted that fastenings 23 may be positioned in any of the three alined openings 13 for adjusting the elevation of the secured end of the tubing 14.

As best seen in Figures 3 and 4, a sleeve 24 is axially disposed in the tubing 14 with one end extending through and supported in the elbow 16, as seen in Figure 3, and the opposite end supported by a bracket 25 mounted in the section 17. A shaft 26 is journaled in the sleeve 24 and has a screw conveyor 27 connected to one end and positioned in section 17 adjacent the open mouth 19. The opposite end of shaft 26 extends through openings in the plates 28 which are secured to the arms 21. Shaft 26 at this end connects with a double universal joint 29 which forms a part of the power take-off shaft 30 which is connected to the driving means of the tractor 10 for driving shaft 26 and the impeller 27 regardless of its angular position relatively to the tractor.

A derrick or hoist 31 is secured to the frame 11 and extends upwardly therefrom. Derrick 31 is provided at its upper end with a pulley 32 and intermediate of its ends with a winch or hoist 33 including a crank 34 and a pawl and ratchet 35. A cable 36 is connected to the winch 33 and is trained twice over the pulley 32 and connected to a hoist block 37 in the conventional manner. Hoist block 37 is provided with a hook 38 which engages the eyelet 39 on section 17 for supporting the pump tubing 14 adjacent its free end.

As best seen in Figure 2, end 16 of the pump tubing 14 is connected to one end of a pipe line 40 which extends along one side of the vehicle 10 and may be suitably supported thereby in any suitable manner, not shown. The pipe line 40, only a portion of which is illustrated, may be of any desired length and forms a conduit for conveying the water pumped through the tubing 14.

From the foregoing it will be obvious, that the winch 33 may be operated for raising tubing 14 on its pivot 23 to lift the end 18 above the ground level so that the apparatus may be readily

5 moved to a point where it is to be used, after which winch 33 can again be operated to lower end 18 until mouth 19 is submerged in the body of water to be pumped and the impeller 27 may
10 then be actuated through operation of the tractor motor, not shown, to pump water through tubing 14 and pipe line 40 for either draining or irrigating land. Tubing 14 may be lowered or raised a substantial distance so that end 18 may be readily submerged under normal conditions.
15 The mouth 19 is so shaped that it may be completely submerged in very shallow water and is adapted to be disposed in a plane parallel to the earth's surface when slightly below such a point so that the apparatus may be efficiently operated for pumping very shallow streams or rivers or for completely draining swamp land.

20 Various modifications and changes may obviously be made and are contemplated, as the drawings and description are only intended to illustrate a preferred embodiment thereof, and the right is therefore reserved to make such changes as fall within the spirit and scope of the invention as hereinafter defined by the appended claims.

25 I claim as my invention:

30 1. An apparatus of the class described comprising a frame adapted to be mounted on a motor driven vehicle, a pump casing pivotally mounted on the free end of said frame and projecting therefrom, a shaft journaled in and extending substantially through said casing, a worm conveyor connected to one end of said
35 shaft and disposed in said casing adjacent its inlet end, a universal shaft connected at one end to the opposite end of said first mentioned shaft and adapted to be connected at its opposite end to a power take-off shaft connected to the driving means for said vehicle for operating said

conveyor, and means mounted on said frame for adjustably supporting the pump casing.

2. In a portable pumping apparatus, a frame formed of sections, one end of one of the sections being adapted to be supported by a tractor and projecting therefrom, the opposite end of said section being pivotally connected to one end of a second section, a pump tubing fixedly secured to the free end of said second section adjacent one of its ends, a shaft extending through said tubing and journaled therein, pumping means connected to said shaft and disposed in said tubing adjacent its free end, power take-off means including a universal driving shaft connecting said first mentioned shaft, at a point substantially in line with the pivotally connected ends of the frame sections, to the driving means of said tractor, and means for adjustably supporting the free end of said tube.

20 3. A device as in claim 2, said supporting means comprising a derrick mounted on and projecting upwardly from said first mentioned frame section and provided with a winch, and a hoisting block and cable connecting said winch to the free end of said pump tubing for adjustably supporting it relatively to the tractor.

25 4. An attachment for use with tractors, said attachment comprising a frame mounted on a tractor and comprising sections pivotally connected in end to end relationship, the free end of one of the sections being secured to the tractor, a pump tubing fixedly secured adjacent its outlet end to the other frame section, pumping means disposed in said tubing, power take-off means connecting said pumping means to the driving means of said tractor, and hoisting means mounted on said frame and connected to said tubing for adjustably supporting it relatively to the tractor.
